[57] CLAIM

The ornamental design for a portable computer, as shown and described.

DESCRIPTION

FIG. 1 is a front top right side perspective view of a portable computer with the keyboard cover and display panel pivoted to an opened position showing our new design;

FIG. 2 is a rear, bottom and left side perspective view thereof;

FIG. 3 is a front, top and right side perspective view thereof with the cover and display panel in closed position; and

FIG. 4 is an enlarged right side elevational view thereof.

Fig. 1
